(57) **CLAIM**

The ornamental design for a power rack attachment, as shown and described.

DESCRIPTION

FIG. 1 is a front, top perspective view of a power rack attachment, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the power rack attachment, which form no part of the claimed design.

1 Claim, 8 Drawing Sheets(56)
